Primary Examiner — Christian P. McLean*(74) Attorney, Agent, or Firm* — DLA PIPER LLP (US); Blake W. Jackson(57) **CLAIM**

The ornamental design for a box, as shown and described.

DESCRIPTION

FIG. 1 is a front perspective of a box according to the new design;

FIG. 2 is a front elevational view thereof;

FIG. 3 is a rear elevational view thereof;

FIG. 4 is a right elevational view thereof;

FIG. 5 is a left elevational view thereof;

FIG. 6 is a top plan view thereof; and,

FIG. 7 is a bottom plan view thereof.

The broken lines illustrate portions of the box and form no part of the claimed design.

1 Claim, 6 Drawing Sheets(56)
